HAROLD R. HAYDEN, OF BROOKLYN, NEW YORK

RADIO DIAL CONTROL

Application filed November 18, 1929. Serial No. 407,881.

This invention relates to radio receiving apparatus and more particularly to the control and indicators for such apparatus, customarily employed in tuning the radio receiving system to receive the desired incoming signals.

Indicators for showing the adjustment of tuning condensers in radio receiving sets usually consist of a dial and pointer, the dial having graduations or other indicia marked thereon and cooperating with the pointer for indicating the position of adjustment. One object of the present invention is to provide an improved dial control comprising a plurality of dials or dial indicators upon which may be marked indicia of different kinds. These indicia may comprise in part indications of angular adjustment of the condensers in degrees of arc or in the wave length or frequency of incoming signals as well as the call letters of different broadcasting stations. As there are many different broadcasting stations in operation and the particular stations received will generally depend to a large extent on the particular locality in which the receiving set is used I provide a means whereby the call letter indications may be readily applied to or removed from one of the dials or indicators.

In the particular embodiment of my invention herein disclosed I employ a plurality of dials, one of which is preferably a drum dial located back of the panel or outer wall of the receiving set cabinet. A second dial is employed which is preferably located outside the front panel or in such a position that call letters of different broadcasting stations or other position indicators which it may be desirable to change, may be readily applied to and removed from this dial. Also I provide suitable means for moving the several dials proportionately so that each will give the correct indication at all positions of adjustment.

The dials cooperate with pointers or similar parts for indicating the adjustment and I preferably mark the indicia on the dials or mark the pointers, or both, with luminous paint so that the adjusted position indication

Other objects and advantages of my invention will appear from the following description taken in connection with the accompanying drawing wherein

Figure 1 is a front elevation of a dial control for radio receiving sets embodying one form of my invention and showing an internal and external dial, 55

Figure 2 is a sectional view of the line 2—2 of Figure 1, certain of the parts being shown 60 in the elevation,

Figure 3 is an elevation of the structure shown in Figure 1 viewed from the back of the radio cabinet panel, and

Figure 4 is a diagrammatic view showing 65 a modified operating means for moving the dials, particularly for moving the external dial.

Referring to Figures 1 to 3 of the drawing reference character 10 represents the front 70 wall or panel of a radio receiving cabinet and 11 a face or escutcheon plate secured to the panel 10 by screw bolts 13. Bolts 13 extend through and serve to secure to the back of the panel 10 a rear supporting plate 16. Secured to the plate 16 are brackets 20 which extend inwardly from the plate and carry on their inner ends the rotatable drum dial 22. Dial 22 is marked around its periphery, preferably with luminous paint, with graduations 24, a portion of which are visible through a window 26 in the escutcheon plate 11. The side walls of the window 26 are formed with inwardly extending projections 27 which form pointers adapted to cooperate with 80 graduations on the drum dial 22 to indicate the position of this dial.

Formed on the outside of the front plate 11 is an arcuate portion 30 which forms a stationary dial. This dial may be marked 90 with graduations in any desired manner and means is provided whereby call letters of different broadcasting stations may be applied to any point of the dial or removed therefrom as desired. For this purpose an arcuate portion 30 may be formed along its length with a surface which may be easily marked and from which the marks may be easily erased or, if desired, such portion may be formed as a holding frame of stamped 95 100

sheet metal formed with an opening along one edge into which frame may be slipped at any desired point a label or strip printed with the broadcasting station call letters. Such label would ordinarily have an arrow or similar mark printed thereon so that the label may be accurately positioned along the arcuate portion 30. I have indicated at 32 the call letters of two broadcasting stations.

Adapted to cooperate with the stationary dial 30 is a pointer 33 which is shown as an arm secured to a shaft 34 extending through the plate 11, panel 10 and plate 16, this shaft being rotatably mounted in a bearing sleeve or bushing 36 also extending through the plates 11 and 16 and panel 10.

For the purpose of moving the drum dial 22 and the pointer 33 so that each will indicate the correct position of the tuning condensers or other parts to be adjusted, I provide a hand knob 38 secured to a shaft 40 in any suitable manner as by a screw 42. Shaft 40 is rotatably mounted in a bearing bushing 41 as shown which extends through plate 11, panel 10 and plate 16 and shaft 40 carries at its inner end a small pulley 43 which is spaced from the inner end of the bushing 41. Also secured to the shaft 40, between the pulley 43 and the inner end of the bushing 41 is a small gear wheel or pinion 44.

The shaft 40 serves to drive the drum 22 by means of a cord or belt 45 which passes around the pulley 43. One end of the cord 45 is secured to the interior of the drum 22 as by means of an eyelet 48. From the eyelet 48 the cord passes through an opening 49 in the periphery of the drum, thence part way around the periphery and up over a guide pulley 50 rotatably mounted on the rear plate 16, thence downwardly beneath a similar pulley 51 rotatably mounted on the rear plate 16 at one side of the pulley 43, thence around the pulley 43 and beneath a guide pulley 53, thence around a portion of the periphery of the drum 22 through an opening 54 in the periphery of the drum to the eyelet 56 to which this end of the cord 45 is secured. It will be apparent from the showing in Figures 2 and 3 of the drawing that rotation of the pulley 43 in one direction or the other by means of the hand knob 38 will serve to rotate the drum dial 22 until the openings 49 or 54 in the drum are brought into a position substantially in the plane of the pulleys, this position of the drum 22 being the limiting position of adjustment.

Mounted on the inner end of the shaft 34 is a relatively large gear wheel 60 which meshes with and is adapted to be turned by the pinion 44, the gear 60 and pinion 44 thus serving as an operating connection between the hand knob 38 and the pointer 33.

It will of course be understood that the relative diameters of the pulley 43, drum 22 and

the gear wheels 44 and 60 will be such that as the drum 22 moves completely over the desired range of movement, the pointer 33 will move over the entire length of the dial 30. Inasmuch as the pulley 43 is of relatively small diameter motion of the knob 38 will impart a relatively slow motion to the indicators thus providing for a so-called vernier adjustment.

It is apparent that other means may be employed for operatively connecting the dials to the operating knob or handle 38, thus in certain cases I may employ gearing between the knob 38 and the dial 22 as well as between the knob and pointer 33.

In Figure 4 I show a modified driving means for the drum 22 and pointer 33 wherein the cord or belt which serves as a driving means for the drum 22 also serves as a driving means for the pointer 33. For this purpose instead of employing the gear wheel 60 at the inner end of the shaft 34 I mount on the inner end of this shaft a pulley or drum 65. The cord 45 in its passage from pulley 53 to the drum 22 passes over the pulley 65 and I secure the cord 45 to the pulley 65 so that there will be no chance of slipping between the cord and pulley 65.

It will be clear from the construction illustrated in Figure 4 that the extent of motion of the drum 22 will always bear a certain relation to that of the pointer 33 and possible slipping of the cord 45 on the driving pulley 43 will not interfere with the correct positioning of the drum dial and pointer. In the connection shown in Figure 4 I may omit the pulley 53.

If desired I may provide a second knob on the outer end of shaft 34 so as to provide for a coarse adjustment as well as the fine adjustment secured by the knob 38. If desired either one or both of these knobs may be normally disconnected from their respective shafts but adapted to be clutched to the shafts by pressing inwardly on the knob.

From the construction shown in Figures 1 and 2 it will be readily seen that the several moving parts of the control as well as the supporting plates 11 and 16 may be readily removed from and applied to panel 10 of the casing or cabinet.

Having now described my invention, what I claim and desire to secure by Letters Patent is:

1. In a dial control for radio receiving systems, a panel, having an opening therein, a drum located behind said opening, and having indicia thereon visible through said opening, a dial having indicia thereon, a pointer cooperating with said dial, means for rotating said drum and means for moving said dial and pointer relative to one another, the drum, and the dial and pointer, each having a range of movement over their respective indicia, and the range of each cor-

- responding to movement of the other over the range of the other, being one revolution or less.
2. In a dial control for radio receiving systems, a panel having an opening therein, a drum located behind said opening having indicia thereon visible through said opening, a stationary dial located outside said panel, said dial having other indicia thereon, a pointer cooperating with said dial and means for moving proportionately, said drum and pointer, the drum and pointer each having a range of movement over their respective indicia and the range of each corresponding to movement of the other over the range of the other, being one revolution or less.
3. In a dial control for radio receiving systems, a panel having an opening therein, a drum located behind said panel and having graduations thereon visible through said opening, a dial occupying a plane parallel to that of said panel and having call letters of broadcasting stations thereon, a pointer cooperating with said dial and a common means for moving said drum and proportionately moving said dial and pointer relative to one another.
4. In a dial control for radio receiving systems, a casing having an opening therein, a drum dial located in said casing, a stationary pointer cooperating with said dial, a second dial outside said casing, a second pointer movable over said second dial, and means for moving said drum dial and second pointer proportionately, said second dial having call letters of broadcasting stations removably positioned thereon.
5. In a radio receiving system control, a plurality of dial indicators having indicia of different kinds on the respective indicators, and means for moving the indicators relatively and proportionately to one another, said means including a cord for operating one of the indicators and a non-slip operating connection between the indicators.
6. In a radio receiving system control, a plurality of rotary dial indicators having indicia of different kinds on the respective indicators, a knob and motion reducing connections between the knob and indicators for moving the indicators relatively and proportionately to one another, said indicators each having a range of movement over their respective indicia and the range of each corresponding to the movement of another over the range of said other, being one revolution or less.
7. In a radio receiving system control, a face plate having an opening therein, a drum dial located behind said opening and having indicia thereon visible through said opening, a stationary dial on said face plate beneath said opening, a movable pointer rotatably mounted on said face plate and adapted to cooperate with said stationary dial, a knob rotatably mounted on said face plate and operating connections between said knob and said drum dial and pointer, said connections being located back of said face plate.
8. In a dial control for radio receiving systems, a panel having an opening therein, a drum located behind said panel and having indicia thereon visible in the dark through said opening, a stationary dial having indicia visible in the dark thereon, a pointer visible in the dark adapted to cooperate with said dial and means for rotating said drum and for rotating said dial and pointer relative to one another.
9. In a radio receiving system control, a plurality of dials a common means for moving said dials, said means comprising a cord connected to said dial and means permitting a coarse and fine adjustment of said dials, said last named means comprising pulleys of different sizes for moving said cord.
10. In a radio receiving system control, a plurality of rotary indicators, pulleys secured to said indicators, a belt passing over said pulleys and permanently secured to each pulley, and means permitting a fine adjustment of said indicators, said means comprising a small pulley over which said belt passes.
11. In a dial control for radio receiving systems, a panel having an opening therein, a drum located behind said panel and having graduations thereon visible through said opening, a dial in front of said panel and having call letters of broadcasting stations thereon, a rotary pointer cooperating with said dial, a pulley secured to said rotary pointer, a pulley secured to said drum, an operating pulley, a belt passing over said pulleys and secured to said first named pulleys, said pulleys and belt being located behind said panel and means extending through said panel for operating said last named pulley.
- Signed at New York city, in the county of New York and State of New York, this 15th day of November, A. D. 1929.
